UNITED STATES PATENT OFFICE.

WILLIAM H. WRIGHT, OF PITTSBURGH, PENNSYLVANIA.

JUG COVER.

Application filed June 26, 1924. Serial No. 722,505.

This invention is for an improvement in covers for the tops of syrup jugs or pitchers, and like articles, and relates particularly to that type of metal cover adapted to be removably secured to a glass jug.

A large variety of covers for syrup jugs and pitchers have been devised, and a great number of them are found on the market today. Practically all of the covers found on the market, however, are of a thin sheet metal construction, that is, often disfiguring to the jug, and which generally have a band encircling the jug for retaining the cover in place. Not infrequently is the neck of the jug molded with lugs thereon for cooperation with this band. Molding such lugs on a glass pitcher increases the cost of the molds, and provides a mold of shorter life, and adds to the difficulty of molding, so that the cost of the pitchers is increased.

Furthermore, it is generally more or less difficult to remove the present form of jug covers, so that they frequently stand a long time without cleaning.

More important than this, however, is the fact that present forms of covers generally have spring hinges associated therewith for closing the cover, which hinges frequently become stuck-up with syrup and sugar crystals, so that the cover will not always shut tightly. These spring hinges also are difficult to clean, and the springs often rust or corrode, disfiguring the cover, and they also break, so that the cover does not close.

The present invention has for its principal objects to provide a gravity closed cover, of a neat appearance, having means for limiting the opening movement of the cover beyond a point where it will be closed by gravity, and to provide a simple retaining means for the cover which will permit of ready removal of the cover and which may be easily cleaned, either on or off the pitcher. This cover is not liable to collect syrup and sugar, does not require any expensive modifications in the molds which make the pitchers in order that the cover may be retained on the jug, and may be made far more attractive than the sheet metal covers, at a price sufficiently low to compete with the sheet metal covers, although being somewhat more expensive.

My invention may be readily understood by reference to the accompanying drawings, in which:

Fig. 1 is a side view of a jug or pitcher,

showing a cover embodying my invention applied thereto;

Fig. 2 is a side view of the cover in open position, showing the hinge part of the cover in section;

Fig. 3 is a section in the plane of line III-III of Fig. 1;

Fig. 4 is an enlarged view of the holding clip, with the cover removed, the clip being shown applied to the lug;

Fig. 5 is a top view of the cover; and

Fig. 6 is a top view of the clip.

In the drawings, A designates a glass pitcher or jug having a neck portion a, a pouring lip a', a notch or recess a² in its top, opposite the pouring lip, and a small recess a³ between ridges a⁴ on the side of the neck portion.

The clip for holding the cover in place, and indicated generally at 5, has a substantially semi-circular resilient spring metal member 6 adapted to fit inside the neck of the jug and be slightly compressed thereby, whereby it presses outwardly to frictionally retain the clip in place. Integral with the spring 6 is a central strap 7, which is bent over horizontally and is received in the notch or recess a² in the top of the pitcher. The end portion of this strap is turned down over the outside of the pitcher, as indicated at 8, and has two integral spaced apart ears 9 projecting rearwardly therefrom. These ears are perforated at 10. Part 8 has an inwardly pressed lug 11 that snaps into recess a³, to assist in holding the clip in place.

The cover 12 is preferably a die-casting, and is considerably heavier, as well as far more ornamental, than the usual thin sheet metal covers generally provided. It has a forward extension 13 that covers the pouring lip, and a rear extension 14 that has an integral lug 15 on its under side. This lug extends down between the parallel ears 9, but is spaced a slight distance rearwardly of the vertical part 8 of the clip. A pin 16 passes through the lugs and ears to provide a hinged connection between the cover and the clip. Extension 14 projects back past this pivot, so that when downward pressure is applied thereto, the cover will be lifted. This extension 14, as in most jug covers, is directly over the handle of the pitcher, so that when the handle is grasped, the thumb may be positioned on the extension to depress it. When the extension 14 is depressed, the cover rises, but lug 15 also swings into con-

tact with part 8 of the clip, as shown in Fig. 2, whereby the extent to which the cover may be lifted is limited to a very great extent. It being impossible to lift the cover to a full vertical position, and the cover being relatively heavy, it will always close by gravity.

The clip and cover can be easily removed and replaced, when necessary, for cleaning, and there are no springs to corrode and collect dirt and sugar. The cast cover, furthermore, is much neater and better appearing than the sheet metal covers now in use. In die casting the covers, several of them may be simultaneously produced.

The clip itself, although made of sheet metal, is inconspicuous and does not detract in any way from the appearance of the pitcher.

20 I claim as my invention:

1. A cover for syrup jugs comprising a clip adapted to be secured to the jug, said clip having a curved inner elongated member, a strap extending rearwardly from the curved member and having laterally projecting spaced apart ears, a cover having an extension thereon over the ears, a lug on the extension projecting down between the ears, a pivot passing through the ears and the cover, said lug arranged to make contact with the strap and serving to limit the opening movement of the cover, beyond a point where it will be closed by gravity.

2. A cover for containers comprising a sheet metal clip member, a cast metal cover member, said clip member including an inner engaging portion, a horizontal portion and an outer portion, said latter portion hav-

ing pivot receiving means, and a lug on the cover member pivoted to the said outer portion of the clip and arranged to make contact with the clip to limit the opening movement of the cover beyond a point where it will be closed by gravity.

3. The combination with a syrup jug, of a cover comprising a clip having a curved resilient inner member, a flat strap extending rearwardly from said curved member and received in a recess in the top of the jug, the outer end of the flat strap being turned downwardly, a lug on said downwardly turned end portion received in a recess in the jug, rearwardly extending spaced apart ears on said downwardly turned end portion, a cover for the jug, an extension on the cover projecting back over the ears, a lug on the extension extending down between the ears, a pivot passing through the ears and lug, said lug also serving to limit the opening movement of the cover to prevent it from being raised to a vertical position.

4. The combination with a syrup jug, of a cover therefor comprising a clip having an inner portion with divergent extensions engaging against the inside of the jug, a horizontal strap extending over the top of the jug and received in a notch therein, a downwardly extending end portion on the strap, integral ears projecting outwardly from the end portion, a lug on said end portion, said jug having a recess therein into which the lug projects, and a cover member hingedly supported by the ears on said clip.

In testimony whereof I affix my signature.

WILLIAM H. WRIGHT.
